UNITED STATES PATENT OFFICE.

CLAUDE B. HOSTETLER, OF OSTRANDER, OHIO.

DENTAL TOOL.

1,297,352.

Specification of Letters Patent.

Patented Mar. 18, 1919.

Application filed January 25, 1919. Serial No. 273,038.

To all whom it may concern:

Be it known that I, CLAUDE B. HOSTETLER, a citizen of the United States, residing at Ostrander, in the county of Delaware and 5 State of Ohio, have invented certain new and useful Improvements in Dental Tools, of which the following is a specification.

My invention relates to dental tools; and more particularly to a device for holding 10 tooth crowns, caps, and the like, when the same are being operated upon.

The object of the invention is to so construct the same that it will be durable, efficient, can be easily and cheaply manufactured, the parts composing the same can be easily assembled and disassembled, and as 15 said parts will be constructed of standard sizes they can be easily restored should a part become worn or useless.

20 In the drawings forming a part of the invention, and in which like symbols of reference represent corresponding parts in the several views:—

Figure 1 is an elevation of the device 25 showing the same in its operative position;

Fig. 2 a sectional view of the same, with the parts there separated;

Fig. 3 a view of the perforated elastic tip, composed, preferably of cork, rubber, or the 30 like; and,

Fig. 4 is a view of a modified form of the tip.

In the drawings, 1 represents the handle of the device, having an internally threaded 35 sleeve 2 secured in its upper portion; 3 a portion of the sleeve extending beyond the upper surface of the handle; and 4 the screw-threads in the sleeve. 5 is a perforated collar, having ribs 6 formed in the 40 same; and 7 a counterbore in its lower portion to receive the extension 3 of the handle and thus hold the parts of the device in operative relation.

8 is a wire or rod, preferably angular, as 45 shown to prevent it rotating in the collar 5, said collar having an angular portion 9 to receive the same; and 10 are screw-threads on the rod to engage screw-threads 4 on the collar.

50 12 is a cylinder or tip, of cork, or the like,

formed, preferably, with a flared opening 13, and a perforation 14, adapted to receive rod 8. The flared opening 13 receives head 15 of rod 8, said head, may if desired, be angular, though said construction is not absolutely necessary. 12^a is modification of tip.

16 indicates the crown in its position ready for the hand of the operator.

17 is a milled enlargement on collar 5 for 60 the purpose of holding the same and operating the tool.

The operation of the device will be clear from the foregoing description. The operator grasps the handle 1 and revolves the 65 same holding the milled portion with the other hand, the rod feeding in the meantime into the handle and thus compresses the inner portion of the tip, expanding the same laterally in a uniform manner, producing 70 a perfect working holder for the crown or other element operated upon.

Having now fully described my invention, what I claim as new, and desire to secure by Letters-Patent, is:—

75

1. A dental instrument, consisting of a handle, a collar having an angular interior adapted to be received upon said handle, a rod having an angular portion to operate in the collar, and a tip for the rod, said tip 80 adapted to be expanded when the handle of the device is rotated.

2. A dental instrument, provided with a handle, a collar working in conjunction with the handle, a rod adapted to operate in the 85 collar, said rod formed with a head, and a perforated resilient tip adapted to be received on the rod and expanded by the same when the device is operated.

3. A dental instrument, having a handle 90 provided with a threaded-sleeve, said sleeve extending beyond the top of the handle, a collar formed with a counterbore adapted to receive the extended portion of the sleeve, ribs in the collar, and a rod having threads 95 formed on the same to engage with threads of the collar, and a head on the rod to engage the holding means.

4. In a device of the character described, a handle having a threaded sleeve, a collar 100

adapted to work in conjunction with the handle, means for connecting the collar and handle, a rod within the collar, said rod formed with a top, a perforated expansible tip on the rod, and means for feeding said rod in the handle with which the same is operated.

In testimony whereof I affix my signature in presence of two witnesses.

CLAUDE B. HOSTETLER.
